UNITED STATES PATENT OFFICE.

DOMENICK A. M. SANSOTTA, OF PITTSBURGH, PENNSYLVANIA.

FINGER-TIP PROTECTOR.

1,306,442.

Specification of Letters Patent. Patented June 10, 1919.

Application filed August 6, 1918. Serial No. 248,654.

To all whom it may concern:

Be it known that I, DOMENICK A. M. SANSOTTA, a citizen of Italy, residing at Pittsburgh, in the county of Allegheny and State 5 of Pennsylvania, have invented certain new and useful Improvements in Finger-Tip Protectors, of which the following is a specification.

My invention relates to new and useful 10 improvements in a finger tip protector and has for its principal object the provision of a device of this character which is simple and inexpensive in construction and which may be easily connected on a finger.

15 A further object is the provision of a reinforcing strip which may be easily detached for replacing when it has become worn.

With these and other objects in view the 20 invention consists of the novel details of construction and arrangement of parts which will be more clearly understood from the following specification and drawings in which:—

Figure 1 is a side elevation of a hand 25 showing a finger tip protector on a finger and thumb, the protector on the finger being shown in vertical section.

Fig. 2 a plan of the blank with reinforcing strips attached.

30 Fig. 3 a side elevation showing the parts in position upon a finger.

Fig. 4 a horizontal section on the line 4—4 of Fig. 3, and

Fig. 5 a fragmental detail of the blank before folding and without the reinforcing strips.

In constructing my protector I use a blank strip indicated at 1 which may be of any desired flexible material. An extension 2 is 40 formed on one edge, at the top, and buckle 3 is secured thereto by means of a fastening strap 4. An extension 5 is formed on the opposite edge, at the top, and is provided with a plurality of perforations indicated at

45 6 for the purpose as will be presently described. Another extension 7 is provided beneath the extension 5, and spaced therefrom, and said extension is slightly shorter than the extension 5. The strip 1 is also 50 provided adjacent each edge with a plurality of spaced perforations indicated at 8 and a projection or extension 9 is formed at the lower end of the strip for the purpose to be presently described.

55 The blank or strip 1 is adapted to be folded to form a substantially cylindrical mem-

ber as indicated in Figs. 1, 3 and 4 of the drawings and when so folded is adapted to be laced along the vertical edge by means of a lacing 10 which passes through the spaced 60 openings 8 adjacent the edge of the strips. The upper end of the strip, before being folded is adapted to be turned over upon itself as indicated more particularly in Fig. 2 of the drawings so that the extension 5 will 65 overlie the extension 7 as shown and the extension 2 will be on a line with the extension 7. A perforation 11 is formed adjacent the top edge of the strip and a similar opening, not shown, is formed adjacent the lower 70 end of the strip and the projection or extension 9. A reinforcing strip 12 preferably of stout leather, is adapted to be secured to the outer face of the strip 1 by means of a cotter pin or rivet indicated at 13. At the top the 75 cotter pin will pass through the reinforcing strip and through the overturned portion of the strip 1 whereas at the lower end the cotter pin or rivet will pass through the opening not shown, and through an opening 80 formed in the reinforcing strip adjacent the lower end thereof and indicated at 14. When the blank has been folded into the cylindrical form the extension 7 will overlie the meeting edges and be received between the 85 fabric 1 and the overturned portion as indicated more particularly in Fig. 4 of the drawings. When the protector is placed upon the finger tip it is secured in position by means of the extension 5 engaging the 90 buckle 3 and the tongue of the buckle will be received in one of the openings 6. By this arrangement the tip may be secured on fingers of different sizes and as illustrated more 95 particularly in Fig. 1 of the drawings the reinforcing strip will preferably extend beneath the end of the finger as will also the projection or extension 9 on the lower end of the blank.

Having fully described the detailed construction it is thought that the manner of using will be understood. My finger tip protector is of particular advantage to brick layers or other persons lifting objects with the fingers and when the reinforcing strip 12 100 has been worn out it may be easily replaced by detaching the same through means of the cotter pins 13 or rivets. By simply renewing the reinforcing strip the tip may be used for a great length of time. By providing 105 the upper edge folded upon itself it will be seen that the head of the cotter pin or rivet

will not engage with the finger and cause discomfort when the strap has been adjusted. The fabric 1 acts as a backing for the head of the cotter pin and thereby protect

5 the finger.

The foregoing description and drawings have reference to what may be considered the preferred, or approved form of my invention. It is to be understood that I may 10 make such changes in arrangement and combination of parts, material, dimension et cetera, as may prove expedient and fall within the scope of the appended claims.

Having fully described my invention what 15 I claim as new and desire to secure by Letters Patent is:—

1. A finger tip protector comprising a substantially cylindrical member having its upper end folded upon itself and a reinforcing 20 strip secured to the folded portion.

2. A finger tip protector comprising a substantially cylindrical member having its upper end folded upon itself, a reinforcing

strip, and means passing through the folded portion and top of the reinforcing strip and through the substantially cylindrical member and lower end of the reinforcing strip for securing the strip in position. 25

3. A finger tip protector constructed from a blank having an extension on one edge adjacent the top, a buckle secured to the extension, an extension formed on the opposite edge adjacent the top and provided with a plurality of perforations, a second extension formed beneath the perforated extension, 30 the upper end of the blank being folded upon itself, means for connecting the edges of the blank to form a substantially cylindrical member and a reinforcing strip detachably connected to the blank. 35

In testimony whereof I affix my signature in presence of two witnesses.

DOMENICK A. M. SANSOTTA.
